UNITED STATES PATENT OFFICE.

NORMAN FRASER, JOHN FRASER, AND GORDON SCOTT FRASER, OF ARBROATH,
SCOTLAND.

SEWING-MACHINE FOR PLAITED-SOLED SHOES.

1,351,637.

Specification of Letters Patent. Patented Aug. 31, 1920.

Application filed September 24, 1918. Serial No. 255,511.

To all whom it may concern:

Be it known that we, NORMAN FRASER, JOHN FRASER, and GORDON SCOTT FRASER, subjects of the King of Great Britain and 5 Ireland, and residents of Arbroath, Scotland, have invented a certain new and useful Improved Sewing-Machines for Plaited-Soled Shoes, of which the following is the specification.

10 The invention has for its object to provide a simple and effective machine for sewing the uppers of jute and like plaited-soled shoes to the sole.

The improved machine is semi-automatic 15 in action, and the sole with the upper lightly tacked on to it and inside out is guided by hand while in the machine, which however feeds it to space the stitches and inserts and locks the stitches automatically. The needle

20 forming the stitches enters the sole (first passing through the upper) about midway of its thickness, and passing diagonally therethrough issues from the under side of the sole at a determinate distance from its 25 periphery, where the stitch is locked. The sole and upper are presented to the stitching device by hand upon a table so angled relatively to the needle that the latter enters the upper and sole in the direction already set

30 forth, and mechanical means are provided for preliminarily piercing the sole, for advancing the sole step-by-step between stitches and for locking it in place while each stitch is being formed. The mechanism 35 operating the needle and the piercing awl and the mechanism operating the shuttle carrying the locking thread and the shuttle itself are of substantially well-known form adapted to suit their specific uses.

40 An example of a machine made according to the invention is shown on four accompanying sheets of explanatory drawings, Figures 1, 2 and 3, Sheets 1, 2 and 3 being respectively a plan, a front elevation and 45 an end elevation, while Figs. 4 to 8, Sheet 4, are views of details to an enhanced scale.

In this example, the sole with its lightly tacked on upper is received on an inclined table A. Here it is pressed by the operator 50 up against a spiked feed roller A¹ on a shaft A² driven by bevel gear A³ (Fig. 7) from a shaft A⁴ which shaft is operated by a bell-crank ratchet device A⁵ from a cam A⁶ by means of a link A⁷ and lever A⁸ pivoted 55 on the machine framing and bearing a

tappet roller A⁹ engaging the cam A⁶, (Figs. 2 and 3). The shaft A⁴ is held stationary (except when urged by the ratchet device A⁵) by a brake band and weight A¹⁰ (Fig. 7) engaging the periphery of a drum A¹¹ 60 on the shaft A⁴. This spiked roller A¹ engaging the edge of the sole feeds it between successive stitches performed by the needle.

Beneath and reciprocating up through an aperture in the table A is a spiked bar B (shown in detail in Fig. 7) carried on a link B¹ pivoted on the machine frame and on a lever B² on a shaft B³. This shaft B³ is rocked by the cam A⁶ (which operates the roller A¹ by way of a lever B⁴ pivoted on 70 the machine frame, a tappet roller B⁵ thereon and a link B⁶ connecting the lever B⁴ with a lever B⁷ (Fig. 3) on the shaft B³. A spring B⁸ in tension between the lever B² and the machine frame serves to keep the 75 tappet roller B⁵ in contact with its cam and to perform the return stroke of the parts.

The cam A⁶ is fast on a shaft C carried in the machine framing, and on this same shaft is fast an internal cam C¹ with which there 80 engages a tappet roller C² on a lever C³ pivoted on the machine framing and connected by a link C⁴ to a needle bar C⁵ sliding in upright guides C⁶ and carrying the needle C⁷. The needle is served with thread 85 from a roll C⁸, which thread passes through an eye C⁹ and a pressure device C¹⁰ to a tensioning device shown separately in Figs. 5 and 6 and consisting of a pair of disks C¹¹ with fingers slotted in their peripheries and 90 bent oppositely. These disks carried between washers on a spindle C¹² are forced together to grip the thread by a spring C¹³.

The thread thence passes through a pincer-like device (Figs. 4 and 7) consisting of a fixed blade D and a pivoted blade D¹ urged toward it by a spring D². This device is carried on an arm D³ on a boss D⁴ rocking on a pin and having a second arm D⁵ connected by a link D⁶ to a tappet lever 100 D⁷ operated by a cam D⁸ on the shaft C against the tension of a spring D⁹—the whole device serving in well-known manner to take up slackness of the thread during the upward movement of the needle.

The stitch through sole and upper is locked in usual manner by a locking thread passed through the needle formed loop of the stitching thread in usual manner. This thread is carried in a shuttle E (Figs. 7 110

and 8) of usual form reciprocated in a race E¹ by means of a link E² which connect it to a lever E³ pivoted in the framing and bearing a tappet roller E⁴ which engages a cam E⁵ (Figs. 1 and 3) on the shaft C.

The shaft C is driven from a lay-shaft F (bearing fast and loose pulleys F¹, F² for a belt) by means of a spur wheel F³ engaged by a pinion F⁴ on the shaft F.

10 The operation of the machine is as follows:—The sole is held upon the sloping table A and pressed firmly against the spiked roller A¹. The spiked rod B first enters followed by the needle C⁷ from the other side. The needle then retires followed by the rod B and finally the spiked roller A¹ rotates feeding the sole forward for the next stitch. The stitch is formed and locked in usual manner.

15 20 What we claim is:

1. In a machine for sewing uppers to jute or like soles to form shoes, in combination a vertically reciprocated sewing needle,

an inclined work table to receive the sole and upper so positioned that the needle 25 enters the edge of the sole diagonally and passes through the sole inward and toward the center thereof, a vertically reciprocated spiked bar adapted to pierce the sole in a direction opposite to that in which the 30 needle enters, and a spiked roller at substantially the same inclination as the work table and adapted to feed the sole forward between successive stitches, as set forth.

2. In the combination forming the subject matter of claim 1 hereof, an intermittently rotated spiked roller adapted to engage the edge of the sole and feed the latter forward between successive stitches, as set forth. 35

40 In testimony whereof we have signed our names to this specification.

NORMAN FRASER.

JOHN FRASER.

GORDON SCOTT FRASER.
